UNITED STATES PATENT OFFICE.

JAMES F. CURLEY, OF YONKERS, NEW YORK, ASSIGNOR TO CONCRETE STEEL COMPANY, OF NEW YORK, N. Y., A CORPORATION OF DELAWARE.

INSERT FOR CONCRETE CONSTRUCTION.

Application filed February 5, 1921. Serial No. 442,670.

To all whom it may concern:

Be it known that I, JAMES F. CURLEY, a citizen of the United States, and a resident of Yonkers, county of Westchester, State of 5 New York, have invented an Improvement in Inserts for Concrete Construction, of which the following is a specification.

This invention relates generally to concrete construction and more particularly to 10 metallic inserts adapted to be embedded in the concrete to provide means for attaching various devices, such as shaft hangers and the like, to the concrete structure.

One of the objects of this invention is to 15 provide a metallic insert for incorporation in concrete structures that will be of simple construction and inexpensive manufacture and of efficient action when in use.

Another object of this invention is to provide 20 an insert of the above type that may be readily and conveniently incorporated within the concrete mold construction preliminary to the pouring of the concrete and which, in addition to reinforcing the concrete structure of itself, will also distribute 25 the load carried by the insert so as to avoid the concentration of stresses within the concrete itself.

This invention aims also to provide a metallic 30 insert which will give a desirable flexibility as to adjustment and arrangement of the devices that it is desired to support therefrom.

Other objects will be in part obvious or 35 in part pointed out hereinafter.

A preferred embodiment of the invention has been selected herein for purpose of illustration and description, the same being shown in the accompanying drawing, 40 wherein,

Figure 1 is a perspective view showing the metallic insert assembled with its associated anchoring devices.

Fig. 2 is an end view, and

Fig. 3 is a side elevation showing the relation of the insert and its anchoring devices with respect to the securing bolts.

Fig. 4 is a bottom view showing certain details of the construction, and

Fig. 5 is an end view of the insert, illustrating one stage of the manufacture thereof.

Fig. 6 is an end view in part of the insert, showing a preferred means for closing the end of the insert, and

Fig. 7 is a sectional view of the closure 55 taken on the line 7-7 of Fig. 6.

In reinforced concrete construction of mill or factory buildings, it is desirable to provide the walls and principally the ceilings of such structures with means whereby various 60 devices, such as shaft hangers and the like, may be readily and positively secured thereto without necessitating the use of expansion bolts and the like, which weaken the concrete structure at their points of application and which also form only an inefficient 65 means of support.

Furthermore, it is advantageous to reinforce the concrete structure at the points of support and also to provide a means whereby a greater and more convenient flexibility of adjustment and arrangement is afforded than is possible in the case where devices such as expansion bolts alone are relied upon. According to this invention a longitudinally extending member 10 of substantially 70 U-shaped cross section is provided, whereby the desired flexibility as well as reinforcement of the structure, is readily attained. The U-shaped member 10 is preferably made of steel and is conveniently made first by rolling into the form shown in cross section in Fig. 5. It will be noted that member 10 is rolled in such manner as to provide a pair of ledges 11 and 12 on one 75 face thereof and a second pair of ledges 13 and 14 upon the other face of the member 10, and preferably, though not necessarily, opposite the individual members of the pair 80 11 and 12. The member 10 is furthermore 85 rolled to provide a pair of upstanding flanges 15 and 16, the several ledges and the flanges extending longitudinally throughout 90 its extent. The member 10 having been given its preliminary form as above described is thereupon further rolled or otherwise formed to give it a substantially 95 U-shaped cross section, as is clearly shown in Fig. 2, the formation being made in such manner that the ledges 11 and 12 extend 100 inwardly between one another from the interior faces of the two legs of the U-shaped member 10 and that the ledges 13 and 14 and flanges 15 and 16 extend outwardly 105 from the exterior faces of the legs of the member 10.

The several proportions given the interior dimensions of the U-shaped member

10 are so chosen that the space within the U-shaped member 10 and the ledges 11 and 12 will conveniently accommodate the enlarged portion or head 17 of a suitable fastening device, herein illustrated as a bolt, the shank 18 of which is freely accommodated between the ledges 11 and 12 and may extend downwardly therebetween.

10 The interior ledges 11 and 12 are preferably interrupted or cut away at suitable intervals throughout the length of the U-shaped member 10, which may be made up in any convenient or suitable lengths. Thus, in Fig. 4 the interior ledges 11 and 12 are shown as recessed or cut away at 19 and 20, the interruption in the ledges being of sufficient extent to permit the entry therethrough of the upper enlarged portion or head 17 of the bolt.

20 The ledges 13 and 14 and the outwardly extending flanges 15 and 16 upon the exterior faces of the legs of the U-shaped member 10 preferably extend continuously throughout the entire length of the insert 10 and form a groove on the exterior of each leg of the member 10 as for example between the ledge 13 and the flange 15 for a purpose to be hereinafter described. The flanges 15 and 16 are provided at suitable intervals with apertures 21.

25 Suitable anchoring devices, such as the inverted U-shaped members 22, are provided with inwardly extending ends 23 adapted to enter the grooves upon the exterior face of the U-shaped member 10 and adapted also to engage the exterior ledges 13 and 14 to support the insert 10 within the concrete and to distribute the load carried thereby throughout the mass of concrete immediately surrounding the insert 10. A suitable 30 number of anchoring devices 22 are provided and distributed at suitable intervals throughout the length of the U-shaped member 10 to insure the proper distribution 35 of stresses throughout the concrete structure.

40 Figure 1 illustrates in perspective the relation between the U-shaped member 10 and the anchoring devices and illustrates also the manner of assembling the several parts with 45 relation to the concrete mold previous to the pouring of the concrete. The insert 10 is placed upon the ceiling form 24, assuming that it is desired to provide the ceiling of a concrete structure with the fixture supporting means of this invention, the flanges 15 and 16 contacting with the mold 24 and forming the means whereby the insert 10 is securely positioned with respect to the mold as by means of nails or screws extending 50 through the openings 21 provided in the flanges 15 and 16. The anchoring devices 22, if not already attached, may now be placed in position so that the inwardly extending ends 23 thereof engage the external 55 grooves upon the legs of the U-shaped mem-

ber 10 and contact with the exterior ledges 13 and 14.

To prevent the concrete from entering the insert 10 endwise during the pouring thereof, a suitable closure 25, more clearly shown in Figs. 6 and 7, is provided and may be conveniently formed of sheet metal bent into the shape shown in Fig. 7 to provide an inwardly extending portion adapted to enter and fit into the end portion of the insert 10 between the upper portion thereof and the interior ledges 11 and 12. The member 25 may be so proportioned with respect to the end section of the member 10 that the spring of the metal thereof will securely hold it in position and will avoid the necessity of additional securing means. The member 25 is obviously used where the insert 10 extends only throughout a fraction of the extent of the ceiling of the concrete structure and may or may not be used where the insert extends throughout the entire dimension of the ceiling.

The concrete having been poured and having set, will be found to engage the U-shaped member 10 at the groove extending exteriorly throughout the length of the legs of the member 10 and will securely hold the insert 10 embedded therein. The insert 10 is thus laterally supported in the concrete by the exterior ledges 13 and 14.

The stresses due to the load which may be carried by the insert 10, as will be herein-after more clearly described, are preferably distributed throughout the mass of concrete 100 immediately surrounding the insert 10 by means of the inverted U-shaped anchoring devices 22 which, being engaged and surrounded by the concrete, distribute throughout the concrete the stresses transferred 105 from the insert 10 to the anchoring devices 22.

Upon the removal of the mold, the interior of the insert 10 will be exposed together with the lower faces of the flanges 110 15 and 16. The interior ledges 11 and 12 may then form the supporting seat for the heads 17 of any desired number of fastening devices or bolts 18, which it may be necessary to employ to suspend from or secure 115 to the hinging features, such as shaft hangers and the like. The cut away portions or recesses 19 and 20 of the interior ledges 11 and 12, being located at convenient intervals throughout the length of member 10, provide a simple and convenient manner for inserting the bolts 18 within the insert 10 and permit of a desirable flexibility of adjustment and positioning thereof throughout the extent of insert 10 without disturbing such 120 fixtures as may also have been positioned and secured. The load transmitted to the insert 10 by the fastening devices or bolts 18 is distributed substantially throughout the length of the insert itself and in turn is 125 130

distributed throughout the concrete structure surrounding the anchoring devices 22 and the exterior ledges 13 and 14.

The member 10 having a cross section 5 which is substantially U-shaped or channeled, offers considerable resistance to stresses and hence functions not only to distribute the stresses imposed upon it by the bolts 18, but also functions as a substantial-
10 ly reinforcing member in the concrete structure itself.

It will be noted that there is as above provided in this invention an insert of simple and inexpensive construction and of 15 highly efficient action. It will also be noted that the several objects, as well as others, of this invention and many advantages have been effectively obtained.

It will be understood that the illustrative 20 embodiment of the invention herein shown may be variously modified and the invention may be variously embodied within the scope of the following claims.

I claim as my invention:

25 1. An insert for concrete construction of the character described comprising a channel having parallel side walls with opposed ledges projecting respectively outwardly and inwardly from each side wall in a plane spaced from the top and bottom of said channel, the inwardly projecting ledges being
30

arranged to receive and retain a bolt head and being recessed at opposite points to permit the insertion and removal of a bolt head, and the outwardly projecting ledges 35 being arranged to be anchored in the concrete; and a flange parallel to the opposed ledges projecting from the outer edge of each side wall and arranged to be secured against a form, substantially as described. 40

2. An insert for concrete construction of the character described comprising a metal strip having ledges projecting from opposite sides thereof along spaced parallel lines and flanges projecting from one side thereof at 45 the edges, said strip being of bent form with the two portions thereof from which said ledges and flanges project lying in parallel relation and the two ledges which project from the inner side of the folded strip lying 50 in opposed relation in one plane, the construction being such that the strip may be rolled in flat condition and bent to channel form to provide an insert having inwardly directed bolt-supporting ledges and outwardly directed anchoring ledges and edge flanges, substantially as described. 55

In testimony whereof, I have signed my name to this specification this 3rd day of February 1921.

JAMES F. CURLEY.
